W. BAUSCH & C. G. HAERING.
REFLECTOR AND METHOD OF MAKING SAME.
APPLICATION FILED DEC. 14, 1916.

1,285,901.

Patented Nov. 26, 1918.

UNITED STATES PATENT OFFICE.

WILLIAM BAUSCH, OF ROCHESTER, AND CARL GUSTAV HAERING, OF BRIGHTON, NEW YORK, ASSIGNORS TO BAUSCH & LOMB OPTICAL COMPANY, OF ROCHESTER, NEW YORK, A CORPORATION OF NEW YORK.

REFLECTOR AND METHOD OF MAKING SAME.

1,285,901.

Specification of Letters Patent. Patented Nov. 26, 1918.

Application filed December 14, 1916. Serial No. 137,065.

To all whom it may concern:

Be it known that we, WILLIAM BAUSCH and CARL GUSTAV HAERING, citizens of the United States, residing, respectively, at

5 Rochester and at Brighton, both in the county of Monroe, State of New York, have invented certain new and useful Improvements in Reflectors and Methods of Making Same; and we do declare the following to 10 be a full, clear, and exact description of the invention, reference being had to the accompanying drawings, forming a part of this specification, and to the figures and letters of reference marked thereon.

15 Our invention relates to the structure of optical reflectors which commonly consist of a glass support provided with a reflecting surface. More particularly, our invention relates to re-inforced optical reflectors.

20 One application of optical reflectors in which the structure of the reflector is seriously taxed is in the use of reflectors for search lights. For this purpose a glass shell, usually of spherical or parabolic form, polished on its front and back surfaces, and silvered on the latter surface, is used. This reflector is mounted in a search light projector with its focus co-incident with the light source, which is usually an electric arc lamp.

25 The heat to which this reflector is normally subjected is quite high, as high sometimes as 600 degrees Fahrenheit, and the stresses to which the glass is oftentimes subjected by temperature changes such as are induced 30 after striking and after extinguishing the arc, and by variations in the action of the arc, are tremendous and have often resulted in fracturing the reflector. When the fracture was a mere crack the reflector may have 35 remained intact, but fractures from this cause have sometimes resulted in total disintegration of the reflector.

40 As applied to search lights for military use the reflectors are subjected to still greater abuse, for added to the stresses imposed on the reflector by the expansion and contraction of the material of the reflector by the heat of the light source, are stresses imposed by the transportation of the search 45 light projector from place to place and by gun fire designed to destroy the search light. The effect of transportation on the reflector is much the same as that caused by the heat

of the lamp, the effect of gun fire, however, is more violent, a single shot sometimes sufficient to shatter and wholly destroy a large reflector.

55 It has been found that if the fracture of a reflector could be localized by absorbing as much of the shock as is possible and if the pieces or segments into which the reflector has been divided after fracture can be held together in their original positions, the reflector will still be capable of useful work, for, although the optical efficiency of 60 the reflector will have been affected and reduced by the fracture, its effectiveness for 65 use in a searchlight will have been impaired merely, and not destroyed.

70 One object of this invention is to provide a reflector having an improved reinforcing backing which is comparatively light in weight, and which also preserves substantially the original form of the reflector thus assuring its practical optical efficiency should 75 it be cracked by the heat of the light source, or during transportation, or should it be pierced by gun fire.

75 A further object of the invention is to provide a reflector having a backing which, 80 during or after application to the reflecting surface support, will not distort the support from its initially ground or finished contour thus preserving while uninjured its originally intended optical qualifications and efficiency.

85 A further object of the invention is to avoid the risks of distortion and self-breakage to which reflector supports are liable 90 when they are subjected to stress and strains of compression heretofore used to prevent total disintegration of a cracked or pierced reflector.

95 A still further object of the invention is to provide a reflector backing which may with equal facility and effectiveness be applied to reflectors having either concave, convex or plano form.

In the drawings:

100 Figures 1 to 7 inclusive are fragmentary views of a reflector made in accordance with our invention, showing steps in the process of making the reflector; Fig. 8 is a cross sectional view of the finished reflector.

105 Throughout the drawings, like characters of reference indicate the same elements and

for the sake of clearness, the proportions of the various layers of material have been exaggerated and the materials have been conventionally shown.

5 In carrying out this invention there is applied to a reflector shell A, such as shown in Fig. 1 and usually made of glass, the usual silver film B, also shown in Fig. 1, and over the silver film B is preferably deposited, 10 usually in a plating tank, a protecting and strengthening layer of metal such as copper C, as shown in Fig. 2. To the outer surface of the copper layer C, is preferably applied a coating or layer D, of any suitable adhesive cement or varnish which on 15 drying will form a protective coating for the metallic layers B. C. as shown in Fig. 3. In practice, it is preferred to form the layer D by applying one or more coatings 20 of black varnish or lacquer composed preferably of linseed oil, a coal tar derivative such as asphaltum, and lamp-black, in suitable proportions. These coatings are preferably baked on for a period of about twelve 25 hours. Over the baked varnish layer D, is then preferably applied a coating or layer E, of pigmented varnish as shown in Fig. 4, and which may consist of an adhesive resinous spar varnish such as "Valspar" 30 varnish, to which has been added sufficient zinc oxid to give the mass the consistency of a thick paint, and this applied pigmented varnish layer E is preferably then baked for about four hours. A layer of any suitable 35 reinforcing material, preferably metallic and porous, such as metal gauze F, which may be a copper wire gauze of about twenty mesh, is then smoothly laid over the outer surface of the baked pigmented varnish layer E, as shown in Fig. 5. This gauze F, 40 constitutes the inner re-inforcing material of the reflector backing. One method of applying the preferred copper wire gauze F, is to lay the partly finished reflector face 45 down on a suitable support and after placing the gauze, (which may or may not previously have been formed to fit the contour of the mirror) upon the baked pigmented varnish layer E, the gauze is spread smoothly 50 over and is temporarily held in intimate contact with the layer E. The layer E prevents the gauze from abrading or otherwise marring the reflecting surface. While the gauze is thus smoothly held to the reflector 55 support a comparatively thick layer G of a plastic adhesive or paste is applied to the gauze covered varnish layer E, in such a manner as to permeate and embed the gauze F and to tenaciously adhere to the baked 60 varnish layer E which itself tenaciously adheres to the outer surface of the baked varnish layer D, as shown in Fig. 6. The composition of paste which it is preferred to use for the adhering layer G, consists of 65 equal parts of a pigment such as zinc oxid

and an adhesive resinous spar varnish such as the well known "Valspar" varnish. This composition layer G, is dried atmospherically or by applied heat until it is hard and then it co-operates with the embedded wire gauze layer F and the baked varnish layer E to form the preferred main foundation or re-inforcing framework of the reflector backing. After the composition layer G has hardened, the protruding peripheral portions of the gauze are trimmed off about even with the periphery of the layers E, G. After scraping or otherwise clearing off any superfluous material from the layer G, there is applied to the outer face of said layer and also over the edges of all of the layers G, F, E, D, C, B, and the peripheral edge of the reflector glass or shell A, a layer H of coating material as shown in Fig. 7. For this layer H, it is preferred to use two coats of a suitable varnish or paste such as is commonly used for covering the silvered backs of mirrors, and composed of linseed oil, resinous varnish and a red iron oxid pigment. This layer H may be baked for two hours, and then a final layer I of a liquid coating material is preferably applied over the layer H, as shown in Fig. 8. For this back finishing layer I it is preferred to use a single coat of resinous spar varnish which may be atmospherically dried but is preferably baked for two hours. Either or both layers H, I, especially obviates possible tendency to curling or stripping of edge portions of the backing from the reflector support.

The nature of the reflector shell backing layers and the manner in which they are applied results in a composite re-inforcing shell backing consisting of a plurality of layers as described, each layer being practically integral with the contiguous substance or substances whereby the reflector and its backing are in molecular contact. With this reflector structure, a glass reflector will prove less liable to breakage from concussion since the peculiar backing serves to absorb stress creating vibrations. In the event of local stress being applied to the material of the shell proper, such as is caused by the impact of a projectile, the backing serves to limit the extent of the fracture from the point of impact to a relatively small area. At the same time the backing holds any separated segments or parts formed by the fracture substantially in their original positions, thus effectually preventing optical distortion or shattering of the reflector shell.

A reflector constructed in accordance with this invention is thus more durable than the usual form of reflector since it not only withstands ordinary shocks and stresses without even evidencing their existence by cracking, but even though the reflector be subjected to treatment which makes fracture of the shell

inevitable, the extent of the fracture is greatly reduced and optical distortion or shattering of the reflector shell is prevented. Instead, the individual fragments of the shell are constrained, thus causing the shell to retain substantially its original form. Another feature peculiar to this reflector backing structure is that it is suitable for plano and convex reflectors as well as concave reflectors, and for any form of reflector the backing enables the reflector to withstand shock or stress applied from any direction.

It is obvious that the number and relative arrangement of the backing layers lying between the reflecting surface and the embedded reinforcement may be varied, as for instance, the pigmented varnish layer E, or the baked varnish layer D, may be omitted, but both layers D, E, are preferably used because of the better protection they afford the reflecting surface and of the increased strength they impart to the finished reflector structure.

25 In contradistinction to the hereinabove named prior reflector structure and method involving a constant compressive stress upon the backed reflector support radially inward from or outward toward its periphery, our invention may be practically carried out by first providing a flat sheet of any suitable plastic material which then would be the practical equivalent of the above named pigmented varnish layer E, and laying a suitable re-inforce such as a metallic gauze layer F, upon said sheet, and overlaying said re-inforce and gauze by a second layer of composition such as G, and then rolling the layers together intimately into a single reinforced sheet from which a backing of proper size may be cut and when used for curved reflectors will be pressed into shape to fit the silvered back of the reflector to which it will be later applied and secured by an interposed adhesive coating; or only the layers F, G, of re-inforcing and plastic material may be intimately rolled together in a sheet and a backing cut from it and afterward shaped to fit the silvered surface of any reflector support and be cemented thereto or to a protective varnish coating such as D, first applied to the silvered back of the support.

Having thus described our invention, what we claim is:

1. The combination with a fracturable optical reflector including a support provided with a reflecting surface, of a backing comprising a layer of tenacious material in adhesive contact with the back of the reflector and a layer of tough reinforcing material embedded within said layer of tenacious material, for preventing the entire disintegration of the reflector and minimizing the distortion thereof in event of its fracture.

2. The combination with a fracturable optical reflector including a support provided with a reflecting surface, of a backing comprising a layer of tenacious material in adhesive contact with the back of the reflector and a reinforcing layer of porous tough metal adhesively embedded within said layer of tenacious material, for preventing the entire disintegration of the reflector and minimizing the distortion thereof in event of its fracture. 75

3. The combination with a fracturable optical reflector including a support provided with a reflecting surface, of a backing comprising a layer of tenacious solidified plastic material in adhesive contact with the back of the reflector, and a reinforcing layer of tough porous fabric adhesively embedded within said plastic material in close proximity to the reflecting surface, for preventing the entire disintegration of the reflector and minimizing the distortion thereof in event of its fracture. 80 85

4. The combination with a fracturable optical reflector including a support provided with a reflecting surface, of a backing comprising a plurality of mutually adhering layers of tenacious solidified plastic material in adhesive contact with the back of the reflector, and a reinforcing layer of tough porous fabric adhesively embedded in said solidified plastic material, for preventing the entire disintegration of the reflector and minimizing the distortion thereof in event of its fracture. 90 95

5. In a reflector, the combination with a transparent support having a reflecting surface at its rear face, of an adhesive protecting and strengthening coating applied back of said reflecting surface, a layer of porous reinforcing material overlying said protecting coating, and a layer of strengthening plastic material overlying and adhering to the porous reinforce and the protecting coating and hardened thereon and holding the porous reinforce securely in place. 105 110

6. In a reflector, the combination with a transparent support having a reflecting medium at its rear face, of an adhesive protecting and strengthening coating applied back of said reflecting medium, a porous metal reinforcing layer overlying said protecting coating, and a layer of strengthening plastic material overlying and adhering to the porous metal reinforcing layer and the protecting coating and hardened thereon and holding the porous reinforce securely in place. 115 120

7. In a reflector, the combination with a transparent glass support having a convex rear face, of a reflecting film on said face, one or more protecting and strengthening layers of varnish applied back of said reflecting film, a wire gauze reinforce overlying said varnish, and a layer of strengthening plastic 125 130

material overlying said wire gauze reinforce and the subjacent protecting varnish and tenaciously adhering to and hardened upon them and holding the wire gauze reinforce 5 securely in place.

8. In a reflector, the combination with a transparent glass support provided with a silver reflecting surface, of a protective metal coating deposited upon the silver, one or 10 more protecting and strengthening layers of varnish applied back of the deposited coating, a wire gauze reinforce overlying said varnish, and a layer of strengthening plastic material overlying said wire gauze reinforce and the subjacent protecting varnish and tenaciously adhering to and hardened upon them and holding the wire gauze reinforce 15 securely in place.

9. The combination with a fracturable optical reflector, of a backing for preventing the entire disintegration of the reflector and minimizing the distortion thereof in event of its fracture, comprising a layer of solidified coating material adhering at the back 20 of the support, a layer of tough metallic gauze overlying the outer surface of said layer of coating material, a layer of tenacious adhesive plastic material permeating and adhesively embedding the gauze and adhering to the layer of coating material, and 25 a protective finishing coating applied over the outer surface of said layer of plastic material.

10. In an optical reflector, the combination with a fracturable support having a reflecting surface, of a backing for preventing the entire disintegration of the reflector and minimizing the distortion thereof in event of its fracture, embodying a protective coating 30 applied to the back of said support, a layer of tough metallic gauze overlying the outer surface of said coating, a layer of pigmented varnish permeating and adhesively embedding said gauze and solidified and adhering to the protective coating, a layer of 35 coating composition spread over the outer surface of said solidified pigmented varnish,

and a finishing layer of varnish applied over said coating composition.

11. The combination with a fracturable 50 optical reflector, of a backing for preventing the entire disintegration of the reflector and minimizing the distortion thereof in event of its fracture, comprising a layer of solidified coating material adhering at the 55 back of the support, a layer of tough metallic gauze overlying the outer surface of said layer of coating material, a layer of tenacious adhesive plastic material permeating and adhesively embedding the 60 gauze and adhering to the layer of coating material, and a protective binding and finishing coating applied over the outer surface and peripheral edge of the backing and the peripheral edge of the support to 65 prevent curling or stripping of edge portions of the backing from the reflector support.

12. The method of backing a fracturable optical reflector to prevent its entire disintegration and minimize distortion thereof 70 in the event of its fracture, consisting in covering the back of the reflector with a protective layer, smoothly and closely overlying the back of the reflector thus protected with a layer of porous re-inforcing material, and applying to the latter a layer of adhesive material which is worked into the re-inforcing material to cover it and cause said material to adhere to the underlying protecting layer. 75

13. The method of backing a fracturable optical reflector to prevent its entire disintegration and minimize distortion thereof in event of its fracture, consisting in embedding 80 a tough re-inforcing material in a slab of tenacious plastic material, forming the backing to the contour of the back of the reflector support and securing the corresponding surfaces of the reflector support 85 and the backing together. 90
